UNITED STATES PATENT OFFICE.

JULES FRANCOIS MATHIAS, OF PARIS, FRANCE.

IMPROVEMENT IN PRESSING HATS.

Specification forming part of Letters Patent No. 41,311, dated January 19, 1864.

To all whom it may concern:

Be it known that, I, JULES FRANCOIS MATHIAS, of Paris, in the Empire of France, have invented a new or Improved Apparatus for Pressing Straw and other Hats, of which the following is a specification.

This invention consists in the pressing of hats or bonnets by means of steam or other fluid at a suitable pressure acting upon a flexible diaphragm or cover applied to one side of the hat or bonnet, while the other side is supported by a rigid block or form, by which means a great saving of time and labor is effected, and the grain of the straw or other material of which the hat or bonnet is composed is better preserved. It also consists in certain mechanical means of applying the above system of pressure to the above purpose.

To enable others skilled in the art to make and use my invention, I will proceed to describe its construction and operation.

Figure 1 is a side elevation of the apparatus employed, representing it partly in section. Fig. 2 is a plan of the same.

Similar letters of reference indicate corresponding parts in both figures.

A is a table, on which there is placed a suitable bed, B, for the reception and support of the hat-block C.

D is what may be termed the "block-cover," consisting of a hollow dome, of cast-iron or other strong metal, large enough to cover the block C and contain the vulcanized sheet india-rubber diaphragm E, which is stretched across the bottom of the said cover and secured around the edges thereof in such manner as to make a perfectly-tight joint and form a tight chamber within the cover. This cover is secured to and near the front end of a strong lever, G, which is secured to a transverse shaft H, which is fitted to bearings in standards I J, erected upon the table A. The back end of the lever G is loaded with weights J J, to slightly more than counterbalance the block-cover D, so that the said cover may be raised from the hat-block by the said weights. At the front end of the lever G there is a handle S, by which the operator takes hold of it to pull the cover over the block. The said lever is formed with tenons on its bottom, both in front of and behind the block-cover, to enter

mortises in the bed B, for the purpose of preventing any lateral movement of the cover upon the bed; and horizontal sliding bolts K K are fitted to holes provided in the mortises and tenons to hold down the cover upon the bed, and these bolts are connected with a yoke, L, which is fitted to slide on two fixed horizontal guide-rods, a a, secured to one side of the bed B. This yoke has attached to it a toothed rack, M, which gears with a toothed sector, N, on a horizontal shaft P, which is fitted to bearings in brackets Q Q, bolted to the standards of the table A. This shaft is fitted with a lever R, by which to turn it to make the sector act upon the rack and thereby move the yoke in or out for the purpose of inserting or drawing the bolts. At the top of the cover there is a cock, b, for the admission of steam through a flexible pipe from a boiler.

The operation of the apparatus is as follows: The bolts K K are withdrawn by a movement of the lever R, and the block-cover D allowed to be raised by the weights J J. The block C is then placed on the bed B, and the hat placed over it and covered with a cap of soft, flexible leather. The block-cover D is then pulled down over the block by the handle S, and the steam being at this time shut off from it by the cock b, the elastic diaphragm E stretches easily over the hat. The bolts K K are next slid through the bed and the tenons on the lever G, by moving the lever R in a proper direction and the cover thus secured. The cock b is then opened to admit steam to the interior of the block-cover, and the steam pressing upon the diaphragm E presses it closely around the block and makes it conform thereto, and the pressure is transmitted through the diaphragm and the flexible leather cover to all parts of the hat at the same time. This pressure continued from one to three minutes is sufficient for the finishing of the hat, whereas in the ironing of hats by hand forty-five minutes are in many cases occupied in doing the same work in a less perfect manner. When the pressing of the hat has been performed, the steam is shut off from the block-cover by closing the cock b, the bolts K K are withdrawn to allow the weights J J to raise the said cover, and the block is taken from the bed and the hat removed from it. Hydraulic pressure or the pressure of heated

air or gas might possibly be substituted for steam-pressure in the block-cover; but as heat and pressure are both desirable, I believe that, all things considered, steam-pressure is best adapted to the purpose of my invention.

What I claim as my invention, and desire to secure by Letters Patent, is—

1. The pressing of hats by steam or other fluid acting upon a flexible diaphragm, in the manner substantially as herein shown and described.

2. The combination of the block C, block-cover D, flexible diaphragm E, and lever G, substantially as and for the purpose herein specified.

J. F. MATHIAS.
